BLEACHING AND COLOR STABILIZATION OF FATTY ACIDS AND RELATED MATERIALS

John M. Preston, Gilman, Ill., assignor to General Mills, Inc., a corporation of Delaware

No Drawing. Application November 19, 1956
Serial No. 622,736

2 Claims. (Cl. 202—57)

This invention relates to an improved method for distilling fatty acids.

"Fatty acids" as used in this invention relate to straight chained mono-carboxylic acids containing 6 to 22 carbon atoms. Common sources of these acids are naturally occurring fats and oils, soapstock and tall oil. Illustrative fats and oils are soybean oil, cottonseed oil, corn oil, rapeseed oil, castor oil, linseed oil, sugar cane oil, and so forth. These acids are used extensively in the preparation of soaps, detergents, cosmetics and numerous other uses. It will be appreciated that in many of these applications the color and color stability of the products are of primary importance. Accordingly, fatty acids having the best color and color stability demand a premium price from these users.

It is, therefore, an object of this invention to teach an improved process for distilling fatty acids. The principal advantages of this improved process are that the fatty acids treated in the manner hereinafter described are bleached and have good color reversion characteristics at room temperature and good color stability at elevated temperatures.

Other objects and advantages to the process will become apparent upon reading the subsequent specification.

The principal methods employed to purify fatty acids commercially are crystallization and distillation. This invention deals only with the distillation of these acids at elevated temperatures, i. e., 175 to 300° C. and at reduced pressures, i. e., 4 to 60 millimeters of mercury. It has been discovered that the objects and advantages of this invention may be accomplished by adding hypophosphorous acid and the alkali salts of hypophosphorous acid to the fatty acids prior to their distillation. Sodium and potassium hypophosphite are two illustrative salts.

The steps involved in the practice of this invention are as follows:

Step 1.—Hypophosphorous acid or one of its alkali metal salts is added to the fatty acids prior to their introduction into the stills.

Step 2.—The fatty acids are heated under reduced pressure to vaporize them and simultaneously therewith phosphine is generated when hypophosphorous acid or its alkali salts are heated at distillation temperatures.

Step 3.—The vaporized fatty acids are cooled and condensed to yield the improved acids made possible by this invention.

This invention may be illustrated further by reference to the following examples in which all "parts" are expressed as parts by weight and all "percentages" are expressed as percent by weight, unless specified otherwise.

EXAMPLE I

200 gram samples of technical grade lauric acid from coconut soapstock and coconut oil were distilled at 5 mm. of mercury subsequent to the addition of 0.5% $\text{Na}(\text{H}_2\text{PO}_2)$.

(Note.)—Because of the phosphine generated during

2

distillation it is important to carry out the distillation in a well vented hood.)

In each instance the percent of distillate and residue was in the order of 95% and 4%, respectively. Table I shows a comparison of various color tests run on the treated and the original acids.

Table I

	Coconut Soapstock Crude Lauric Acid		Coconut Oil Crude Lauric Acid	
	Original	Treated Distillate	Original	Treated Distillate
15 Gardner Color	LT 11	LT 1	LT 1	LT 1
Color Stability A ³	NDT 24	NDT 1	NDT 3	NDT 1
Color Stability B ⁴	NDT 7	NDT 4	NDT 7	NDT 2

¹ LT throughout refers to "lighter than" on the Gardner scale.

² NDT throughout refers to "not darker than" on the Gardner scale.

³ The "A" method for measuring color stability is a measurement of the color developed by heating a 25 ml. sample of the fatty acids at 250±5° C. for 30 minutes, cooling to room temperature, and taking a Gardner color reading.

⁴ The "B" method for measuring color stability is substantially the same as the "A" method except that the sample is heated for 3 hours.

EXAMPLE II

300 gram samples of crude cottonseed fatty acids were alemically distilled at a pressure of 5 mm. Hg and a maximum pot temperature of 275° C. To each of these samples was added prior to distillation the amount of

30 solid $\text{Na}(\text{H}_2\text{PO}_2)$ shown in Table II.

Table II

Percent of $\text{Na}(\text{H}_2\text{PO}_2)$ Added	Gardner Color	Color Stability "A"		Color Stability "B"	
		35	35	40	40
0	NDT 8	NDT 12	NDT 16	NDT 16	NDT 16
0.01	NDT 7	NDT 11	NDT 14	NDT 14	NDT 14
0.05	NDT 7	NDT 9	NDT 13	NDT 13	NDT 13
0.1	NDT 7	NDT 9	NDT 13	NDT 13	NDT 13
0.2	NDT 6	NDT 9	NDT 13	NDT 13	NDT 13
0.3	NDT 5	NDT 7	NDT 13	NDT 13	NDT 13
0.4	NDT 4	NDT 6	NDT 11	NDT 11	NDT 11
0.5	NDT 4	NDT 6	NDT 13	NDT 13	NDT 13
1.0	NDT 4	NDT 6	NDT 13	NDT 13	NDT 13
2.0	NDT 4	NDT 6	NDT 13	NDT 13	NDT 13

EXAMPLE III

Crude soybean fatty acids and crude tallow fatty acids were alemically distilled as described in Example II and the results are shown in Table III.

Table III
SOYBEAN FATTY ACIDS

Percent of $\text{Na}(\text{H}_2\text{PO}_2)$ Added	Gardner Color	Color Stability "A"	Color Stability "B"
55 0	NDT 4	NDT 9	NDT 13
2.0	NDT 3	NDT 6	NDT 12

TALLOW FATTY ACIDS

60 0	NDT 2	NDT 5	LT 13
2.0	NDT 1	NDT 3	NDT 11

EXAMPLE IV

65 Hypophosphorous acid was added to 200 gram samples of crude cottonseed fatty acids and the mixtures distilled at 5 mm. Hg and at a maximum pot temperature of 275° C. The hypophosphorous acid was added in the form of a 50% solution. In Sample A the amount of hypophosphorous acid added was equivalent on a mole basis to the addition of 0.1% $\text{Na}(\text{H}_2\text{PO}_2)$ and in sample

3
B to 1.0% Na(H₂PO₂). The results are shown in
Table IV.

Table IV

Sample	Gardner Color	Color Stability "A"	Color Stability "B"
Control	8	12	16
A	6	9	13
B	4	5	9

EXAMPLE V

0.2% Na(H₂PO₂) was added to a crude mixture of fatty acids containing approximately 3% caproic acid, 56% caprylic acid, 34% capric acid, and 7% lauric acid and the mixture distilled in a large scale commercial operation. Table V shows the comparison between the color characteristics of acids treated in the above manner and untreated commercially distilled acids of the same composition.

Table V

	Gardner Color	Color Stability "A"	Color Stability "B"
Treated	LT 1	NDT 6	NDT 11
Untreated	LT 1	NDT 8	NDT 13

In the large scale treatment of acids as in Example V, precautions must be taken to safely vent the phosphine generated. It has been observed, however, that only minute quantities of phosphine will be carried over into the condensed fatty acids.

4
As demonstrated by the preceding Examples, it is possible to improve the quality of distilled fatty acids by the addition of from 0.01 to 2.0% by weight of hypophosphorous acid or its alkali salts. However, the preferred range is from 0.1 to 1%.

5 Therefore, many modifications and variations of the invention as hereinbefore set forth may be made without departing from the spirit and scope thereof and therefore only such limitations should be imposed as are 10 indicated in the appended claims.

What is claimed:

1. The process of distilling fatty acids containing 6 to 22 carbon atoms which comprises adding a compound 15 selected from the group consisting of hypophosphorous acid and the alkali salts of hypophosphorous acid to the fatty acids prior to distillation, heating the fatty acids 20 to 175 to 300% C. at a reduced pressure of from 4 to 60 millimeters of mercury to simultaneously vaporize the fatty acids and generate phosphine, and cooling said vapors to condense the improved fatty acids which have been bleached and have improved color stability at elevated temperatures and good color reversion characteristics at room temperature.

2. The process of claim 1 in which the phosphite compound 25 added prior to distillation is sodium hypophosphate.
